DESIGN FOR A DISPLAY CABINET FOR
GREETING CARDS

Henry J. Loosley, St. Louis, Mo.

Application June 14, 1947, Serial No. 139,690

Term of patent 14 years

(Cl. D80—11)

To all whom it may concern:

Be it known that I, Henry J. Loosley, a citizen of the United States, residing at the city of St. Louis, State of Missouri, have invented a new, original, and ornamental Design for Display Cabinet for Greeting Cards, of which the following is a specification, reference being had to the accompanying drawing, forming part thereof.

Fig. 1 is a perspective view of a display cabinet for greeting cards, embodying my new design;

Fig. 2 is an end view, both ends being the same reciprocally;

Fig. 3 is a front elevational view; and

Fig. 4 is a top or plan view.

I claim:

The ornamental design for a display cabinet for greeting cards, as shown.

HENRY J. LOOSLEY.
